UNITED STATES PATENT OFFICE.

JOHN FREDERICK MATTHEWS, OF DOVER, ENGLAND.

MEANS FOR BUILDING SUBAQUEOUS STRUCTURES, SUCH AS SEA WALLS, DOCK WALLS,
AND RETAINING WALLS, ABOVE AND BELOW WATER, AND THE LIKE.

Application filed March 10, 1920. Serial No. 364,841.

To all whom it may concern:

Be it known that I, JOHN FREDERICK MATTHEWS, a subject of the King of Great Britain and Ireland, and residing at 29 5 Heathfield Avenue, Dover, in the county of Kent, England, have invented a certain new and useful improved means for building subaqueous structures, such as sea walls, dock walls, and retaining walls, above and 10 below water, and the like, of which the following is a specification.

This invention has for its object to provide simple and efficient means whereby sea walls, dock walls, retaining walls and other 15 subaqueous or like structures may be rapidly and cheaply constructed by the use of completed parts which may be constructed in any desired or convenient situation and then transported to the place where the structure 20 is to be built and it is to be understood that while the appended claims recite subaqueous structures only, this term is to be taken as including any structures to which the invention may be applied in practice.

25 The invention comprises a method of constructing such subaqueous or other structures which consists in forming from reinforced concrete, a plurality of grooved piles and a plurality of panels, sections or shutters, and 30 erecting the piles and shutters to form pockets or other suitably shaped spaces or receptacles into which mass concrete or other suitable filling material is inserted.

The invention also comprises subaqueous 35 and other structures comprising a plurality of grooved reinforced concrete piles and panels or shutters fitted into the grooves of said piles to form pockets or other suitably shaped spaces into which mass concrete or 40 other suitable material is filled.

The invention also comprises other details and arrangements hereinafter more particularly referred to.

The accompanying drawings illustrate 45 several modes of carrying out the invention.

Figure 1 is an outside elevation showing one convenient form of pile in accordance with the invention.

Figures 2, 3 and 4 are views showing various forms of reinforcements which may be employed for the piles in accordance with the invention.

Figures 5, 6 and 7 are sectional plans of the reinforcements shown in Figures 2 to 4.

55 Figure 8 is a plan showing a portion of a

structure formed in accordance with the invention.

Figures 9 to 12 are plan views showing various forms of keys which may be adopted for keying the panels or shutters to the mass 60 concrete or other filling, and

Figures 13 to 16 are sectional views of the respective keys shown in Figures 9 to 12.

In carrying my invention into effect in one convenient manner as shown for example in 65 Figure 8, I form my improved structure from a number of grooved reinforced concrete or like piles *a* into the grooves in which are inserted sections, panels or shutters *b* forming spaces or pockets *c* into which 70 mass concrete or other suitable filling material is inserted, the panels or the like *b* being provided with projections or keys or being otherwise suitably arranged or adapted so that they may be keyed or anchored 75 securely to the mass concrete or other filling.

The piles and shutters may be erected or constructed in any suitable locality and when completed may be transported to the place where the structure is to be erected, it 80 being obvious that prior to driving the piles into their intended positions, the foundations for the walls or other structures should be prepared by dredging and (or) blasting to form a grip or trench to meet the conditions of sea beds or those arising from currents and the like.

The piles will be driven at such distances apart from one another and the grooves therein will be dimensioned to suit the dimensions of the completed panels or shutters, and by means of my invention I produce a kind of frame work of moulds or pockets into which mass concrete or other suitable filling material may be deposited 95 from skips or otherwise so that by this method dock walls, retaining walls or other subaqueous or like structures may be readily and rapidly completed.

The piles and shuttering may be suitably 100 constructed, and in this connection I have illustrated several modes according to which the same may be constructed.

In Figures 2 to 4, the main reinforcement may be provided by means of two angles *d* 105 of steel or other suitable material running longitudinally of the piles and adapted to abut on and (or) be secured to a cast iron or other reinforcing shoe *e* situated at the foot of the pile. The angles *d* are bolted to- 110

gether and spaced apart by means of distance pieces *e* located at suitable intervals along the length of the angles, the latter serving as supports for one or more sets of 5 wire or other like transverse or circumferential bracings or reinforcements *f*, *g*, said reinforcements or bracings being helically wound in opposite directions and adapted to be secured to vertical rods *h*' secured to the cast 10 iron or other reinforcing shoe *e*' in the manner shown it being clear that such may be carried from the main angles in any suitable manner.

In the form shown in Figure 2, the angles 15 are punched or otherwise formed with sets of apertures *h*, *i*, for carrying the transverse or circumferential bracings or reinforcements, while in the form shown in Figure 3, I provide for the bracing *f*, tongues or 20 lugs *k* formed by punching in the material, the tongues or lugs being bent alternately in opposite directions as shown in Figures 3 and 6.

Figure 4 is a view of a modified form of 25 reinforcing in which the angles are cut from the outer edges to form tongues *l* which, in a similar manner, are alternately bent in opposite directions as shown.

Such means of providing for the support 30 of the circumferential spiral or transverse wire or other reinforcements serve also as a grip for the concrete of the piles and provide the necessary resistance against stresses set up by the shuttering when the structure 35 is erected, but it will be understood that while various forms have been given by way of example, other suitable forms of reinforcement may be adopted and any desired or convenient method of casting or 40 constructing the piles and shutters may be employed. The reinforcements made in this manner are then placed in a suitable mould and liquid cement is then poured in so that the completed reinforced cement 45 pile assumes the shape indicated by the circumscribing dotted lines in the various figures.

It is preferred to provide means for anchoring the shutters to the mass concrete or 50 other filling, for which purpose I provide keys or projections *m* upon the shutters, such keys or projections being preferably formed in one with the panels or shutters and being strengthened by the reinforce-

ments of the latter, four different types of 55 such keys being clearly illustrated in Figures 9 to 16.

In order to prevent wash of the new concrete filling under water, the concrete should be covered with sheets of canvas 60 ballasted with lead, cast iron or the like, in order to prevent its displacement by rough seas. When the mass concrete is poured 65 into the pockets *c* the panels or shutters are securely anchored thereto by keys or projections *m*, various forms of which are shown in Figures 9 to 16, said keys or projections being preferably formed in one with the panels or shutters and strengthened by having their reinforcements *p* secured to 70 the reinforcement *n* of the shutter, the construction of four different types of keys being clearly shown in the drawings.

It will be understood that the essential 75 feature of the invention is the construction by means of piles and panels, shutters or the like, and the invention is not to be limited to the details of construction hereinbefore given by way of example as these may be modified within wide limits, within the 80 scope of the appended claims, to suit the particular character of structure to be formed or any practical requirements that may have to be fulfilled, and moreover, 85 rubble, sand, clay or other suitable filling material may be adopted in place of the mass concrete hereinbefore referred to.

Having now described my invention, what 90 I claim as new and desire to secure by Letters Patent is:—

1. A subaqueous structure comprising in combination a plurality of spaced reinforced concrete piles, panels secured to and connecting adjacent piles so as to form an enclosed space, filling material inserted in 95 such space, and keying members formed on the panels for the purpose of keying the same to the filling material.

2. For use in subaqueous structures as claimed in claim 1, a reinforced concrete 100 pile comprising angles running longitudinally of the pile, a metal reinforcing shoe situated at the foot of the pile and secured to said angles and distance-pieces spacing said angles apart.

In testimony whereof I have signed my name to this specification.

JOHN FREDERICK MATTHEWS.
